UNITED STATES PATENT OFFICE.

CARL J. VELEY AND WILLIAM S. FORBES, OF KALAMAZOO, MICHIGAN.

WASHING MACHINE.

Application filed October 4, 1919. Serial No. 328,360.

To all whom it may concern:

Be it known that we, CARL J. VELEY and WILLIAM S. FORBES, citizens of the United States, residing at Kalamazoo, county of Kalamazoo, State of Michigan, have invented certain new and useful Improvements in Washing Machines, of which the following is a specification.

This invention relates to improvements in 10 washing machines.

The main objects of this invention are:

First, to provide in a washing machine an improved driving means.

Second, to provide in a washing machine 15 of the oscillating cylinder type an improved gearing whereby the washing cylinder is oscillated through a long stroke, the mechanism being simple, strong and durable.

Third, to provide in a washing machine 20 an improved means for supporting the driving gearing and moving parts.

Fourth, to provide in a washing machine an improved driving means for the wringer used in connection therewith.

Fifth, to provide an improved washing 25 cylinder which is highly efficient and at the same time has no rough or interiorly projecting parts to unduly wear the articles washed.

Sixth, to provide in a washing machine 30 an improved wringer driving and reversing means which may be driven independently of or simultaneously with the washing cylinder.

Further objects, and objects relating to 35 structural details will definitely appear from the detailed description to follow.

We accomplish the objects of our invention by the devices and means described in 40 the following specification. The invention is clearly illustrated in the accompanying drawing, forming a part of this specification, in which:

Fig. I is a front perspective view of a 45 washing machine embodying the features of our invention.

Fig. II is an enlarged detail perspective showing details of the washing cylinder driving mechanism.

Fig. IIIA is a detail side view of the driving parts shown in Fig. II.

Fig. III is a detail view partially in section, showing further details of the washing cylinder driving mechanism.

Fig. IV is a detail view partially in vertical section on a line corresponding to the

broken line 4—4 of Fig. V and Fig. VI, showing details of the wringer driving mechanism.

Fig. V is a horizontal section on a line 60 corresponding to the broken line 5—5 of Fig. IV.

Fig. VI is a detail view partially in horizontal section on a line corresponding to line 6—6 of Fig. IV, showing details of the 65 means for securing the wringer in its adjusted positions.

Fig. VII is a detail view partially in section on a line corresponding to line 7—7 of Fig. III, showing details of the means for 70 engaging and disengaging the cylinder driving connections.

Fig. VIII is a front elevation of the supporting frame for the gearing and cylinder.

Fig. IX is a top view thereof.

Fig. X is a perspective view of the washing cylinder with the cover partially raised.

Fig. XI is a detail longitudinal section thereof on a line corresponding to line 11—11 of Fig. X, the cover being shown in 80 its closed position by full lines, and in partially open position by dotted lines.

Fig. XII is a detail transverse section of the cylinder on a line corresponding to line 12—12 of Fig. X.

Fig. XIII is a detail view partially in vertical section showing the bearing for the rear end of the washing cylinder.

Fig. XIV is a detail side elevation of the body of the machine, showing the cover in 90 its open position by the dotted line.

Fig. XV is a detail end elevation of the washing cylinder looking from the right hand end thereof.

Fig. XVI is a perspective rear view of 95 a slat for a modified form of the washing cylinder.

Fig. XVII is a cross section thereof on a line corresponding to line 17—17 of Fig. XVI.

Figure XVIII is a sectional view on the line 18—18 of Fig. 1.

In the drawing, similar reference characters refer to similar parts throughout the several views, and the sectional views are 105 taken looking in the direction of the little arrows at the ends of the section lines.

Referring to the drawing, we provide a main frame comprising front corner uprights 1, and rear corner uprights 2. The 110 tank or receptacle 3 is mounted within this frame with one end in a spaced relation to

the end door 4, providing a housing or chamber 5. The receptacle 3 is provided with a cover 6 at one end of which are hooks 7 slidably engaging the flanges 9 on the frame. When the cover is withdrawn from the receptacle its hooks 7 engage the loops 10 at the ends of the flanges 9 so that the cover is supported in a vertical position at the end of the machine as shown by dotted lines in Fig. 14.

The washing cylinder comprises a pair of heads 10 and 11, between which the side wall 12 is clamped by means of bolts 13 extending from head to head. The wall 12 is provided with a door opening 14 at one side, the opening being closed by the door 15 complementing the side wall to provide a complete cylinder. The head 11 is provided with a lug 17 with which one end of the door may be engaged or disengaged by longitudinal movement. The wall and door are provided with longitudinal corrugations having perforations 19 in the outer crowns thereof, the inner crown being imperforate. These perforations being arranged in the outer crowns of the corrugations and the inner crowns being imperforate, there is an opportunity for the free passage of air and water through the cylinder, and the articles to be washed are held away from the perforations by means of the corrugations which are relatively small, thereby allowing the water to flow through the articles as the cylinder is revolved or oscillated. The cover is of such width that its outer corrugations overlap the corrugations of the side wall adjacent edges. To secure the door one end is engaged with the retaining lug 17, as stated, while its other end is engaged by the spring catch 20.

We thus provide a cylinder which is light in weight, and at the same time is strong and rigid. The cylinder is provided with journals 21 and 22, journal 22 being supported by the bearing 23. Journal 21 is supported by the bearing 24 which is cut away at its upper side so that the journal 21 may be lifted therefrom, if desired. Journal 21 is provided with a jaw clutch member 25 with which the coacting clutch member 26 of the driving shaft 27 coacts.

Shaft 27 is mounted for longitudinal movement, a shifting rod or a rock shaft 28 having an eccentric pin thereon engaging a transverse slot 30 in the shaft 27, being provided for its actuation. The rock shaft 27 is arranged through the cover 6 which is slotted at 31 to receive the shaft when the cover is closed. The rock shaft has a hand piece 32 at its upper end. A detent 33 supported by the coil spring 34 in engagement with the flattened portion 35 of the rock shaft is provided for holding the rock shaft in its adjusted positions.

65 The bearing 24 is carried by a frame 36

having ears 37 at its corners bolted to the corner uprights 1 and 2. This frame 36 not only carries the shaft 27 and one end of the cylinder but is also provided with a bearing 38 for the shaft 39 of the roller 40 which supports the rack 41 in coacting relation to the driven gear 42 on the shaft 27.

The rack is driven from the crank wheel 43 on the shaft 44, the crank wheel being provided with a wrist pin 45 for the rack. The roller 40 is so disposed relative to the driven gear 42 and the driving wheel 43 as to support the rack in a rearwardly inclined position as shown to coact with the gear. The rear side of the rack traveling on the roller is curved at 46 to permit the oscillation of the rack as the driving gear revolves.

The driving gear 43 is driven from a worm on the shaft 47 which has a pulley 48 thereon, connected with the motor 49 by the belt 50.

The wringer designated generally by the numeral 51 is mounted on the tubular bracket 52 projecting horizontally from the spherical reverse gear box housing 53. The gear box housing is provided with a support comprising a tubular part 54 formed integrally with the housing and the extension tube or housing 55 secured to the part 54. This extension 55 rests in a bearing-like support 56 on the gearing supporting frame.

The wringer shaft 57 is connected by the coupling 58 with the reverse gear shaft 59, the wringer shaft being arranged in the bracket 52 which constitutes the housing therefor.

The reverse gear shaft 59 is provided with a pair of bevel gears 60 coacting with the bevel gear 61 on the end of the shaft section or member 62, provided with bearings in the tubular support in the reverse gear box. The shaft member 63 is provided with a gear 64 on its lower end meshing with the worm 65 on the shaft 47. The shaft members 62 and 63 have a slip driving connection at 66, the gear box support being arranged to seat in the bracket 56 so that driving connection is made merely by arranging the housing support on the bracket. The wringer is thus supported so that it may be swung around on an axis common to that of the wringer driving shaft.

To reverse the wringer, we provide a clutch 67 which is splined to the reversing shaft to coact with either of the gears 60, thereby securing the reverse driving means for the wringer no matter what the position of the wringer may be, and as stated, it may be swung about to any position desired.

The clutch member is shifted by means of the rocker 68 arranged through the top of the gear box and provided with a handle 69.

We provide means for retaining the

wringer in its adjusted positions, the means being illustrated, consisting of the band clamp 70 having ears 71 at its end through which the screw 72 is arranged, the screw 5 being extended at the side of the housing and provided with an actuating hand piece 73.

In the washing cylinder modification shown in Figs. XVI and XVII, the cylinder 10 is made up of a series of slats 74 having corrugation-like ribs 75 on their inner sides, the slats being secured to the heads by suitable means not illustrated. These slats have 15 perforations 76 between the ribs.

To facilitate the drawing off of the water from the receptacle, we provide a hose 77 secured to the outlet of the tank provided with a valve 78 at its outer end so that the water to be drawn off may be delivered 20 through this hose to a pail or otherwise as desired. When not in use, the hose may be hung up inside of the gear housing as shown in Fig. I.

We have illustrated our improvements in 25 an embodiment which has proven very satisfactory. We have not illustrated or described other modifications and adaptations which we contemplate, as we believe the dis-

closure made will enable those skilled in the art to which this invention relates to adapt 30 or embody the same as may be desired.

Having thus described our invention, what we claim as new and desire to secure by Letters Patent, is:

In a structure of the class described, the 35 combination of a main frame comprising corner uprights, a receptacle mounted there-in with one end in a spaced relation to the plane of the adjacent corner uprights, a door hinged to one corner upright to close 40 against the other providing a gear housing, and a gear supporting frame formed as an integral casting mounted upon said corner uprights within said housing and independent of said receptacle, said supporting frame 45 having an integral gear box at its lower end adapted as a lubricant receptacle.

In witness whereof, we have hereunto set our hands and seals in the presence of two witnesses.
